UNITED STATES PATENT OFFICE.

WILLIAM M. JEWELL AND OMAR H. JEWELL, OF CHICAGO, ILLINOIS.

FILTER.

SPECIFICATION forming part of Letters Patent No. 447,568, dated March 3, 1891.

Application filed December 1, 1890. Serial No. 373,109. (No model.)

To all whom it may concern:

Be it known that we, WILLIAM M. JEWELL and OMAR H. JEWELL, citizens of the United States of America, residing at Chicago, in the county of Cook and State of Illinois, have invented certain new and useful Improvements in Filters, of which the following is a specification, reference being had therein to the accompanying drawings.

10 This our invention relates to filters principally for private dwelling use; and it has for its object to provide such a filter that can be secured anywhere against the wall of the kitchen or any other room and connected with 15 the hydrant, and which in an easy manner can be readily cleaned of accumulated impurities; and with these objects in view our invention consists of the novel devices and combinations of devices hereinafter described and specifically claimed.

20 In the accompanying drawings, Figure 1 represents a vertical cross-section of the entire apparatus; Fig. 2, a plan view of the same, and Fig. 3 a plan of the grate for the filtering material.

25 Corresponding letters of reference in the several figures of the drawings designate like parts.

30 A denotes a ring having arms with rectangular flanges *a*, by which said ring is secured with wood-screws against the wall. This ring A forms the support for the filter, and upon it is secured by screws the bottom flange of the cylindrical chamber B, provided with a 35 somewhat funnel-shaped bottom *b* integral therewith, the central nozzle *c* of which is internally screw-threaded. In its top the chamber B is expanded to provide a shoulder *d*, above which the expanded portion is inter- 40 nally screw-threaded, and upon this shoulder is placed the cover D, a packing-ring of sheet-rubber being interposed for insuring a hermetic joint, and this cover D is forced and held down to its seat by a ring E, exteriorly 45 screw-threaded to engage the internal screw-threads of chamber B, and is provided with radial handles *e*, that extend from the top thereof.

50 In the center of cover D is screwed a stuffing-box *f*, tapped for a screw-stem F and fitted with a screw-nut gland *g* for forming a

tight joint around such screw-stem F. This screw-stem F has secured to its upper end a hand-wheel *h*.

Surrounding the bottom *b* of chamber B is 55 provided an annular recess for a rubber ring *i*, upon which is seated the exterior ring of a grate G, provided with cross-bars *j*, that are narrowed toward their upper face, providing the support for the filtering material. This 60 filtering material consists of a perforated sheet of metal *k*, upon which are placed sheets or layers of paper or other fibrous or porous material *l*, and upon this filtering material is placed a somewhat bell-shaped cup H, the 65 outer rim of which coincides with the ring of grate G, so the peripheral edges of the filtering material are packed between the said ring of grate G and the outer rim of cup H. This cup H to its center has a projecting boss 70 conically concaved for receiving the point of screw-stem F, by which it is forced downward to compress the edges of the filtering material. Said cup H is perforated with holes *m* for admitting the water fed through a pipe I, tapped 75 through chamber B and provided with a valve *n*.

J is the reservoir for the filtered water, being a cylindrical vessel closed on top and bottom and having a central screw-neck to its top 80 that enters and is coupled with the nozzle *c* of chamber B. To its bottom center the reservoir J is provided with a faucet *p* of any usual construction, through which water can be drawn in desired quantities. This reservoir 85 J also has to its top, at one side, a check-valve *q*, so arranged that it will admit air, but will close against the escape of air or water. The water admitted through pipe I into the chamber B, after passing through perforations *m* 90 in cup H, must filter through the fibrous or porous sheets *l* before it can escape through neck *o* into reservoir J. The atmospheric air contained in such reservoir will be compressed by the water entering to a pressure equal to 95 the pressure of the supply, after which no more filtering will take place until some of the water has been drawn from the reservoir through faucet *p*, when at once a corresponding amount of water will be filtered again, and with emptying the reservoir entirely, and thereby exhausting part of the air, an equal amount of

air will be admitted through valve *q*. Thus it will be seen the water in this filter will be under pressure for drawing small amounts equal to the pressure in the hydrant. From 5 time to time the filtering material must be cleaned of the accumulating impurities from the water settling thereon. This is readily accomplished by closing valve *n*, then partly unscrewing screw-stem *F*, next by unscrewing 10 and removing ring *E*, and finally by removing cup *H*, when the filtering material can be taken out and washed or replaced by new material, and then the parts can be connected again in the reversed order they were removed. 15 This apparatus, as will be readily seen, is very simple and convenient for the purpose designed, and its great advantage consists in the easy manner of keeping it clean, and thereby insuring its perfect and satisfactory 20 operation.

What we claim is—

The combination, with chamber *B*, having discharge-nozzle *c* and cover *D*, removably secured by screw-threaded ring *E*, and having screw-stem *F*, of grate *G*, supporting diaphragms of filtering material *l*, of perforated cup *H*, covering and holding the diaphragms *l* and being compressed by screw-stem *F*, of a water-supply pipe communicating with chamber *B*, and of a reservoir connected with nozzle *c*, all substantially as set forth. 25 30

In testimony whereof we affix our signatures in presence of two witnesses.

WILLIAM M. JEWELL.
OMAR H. JEWELL.
